Patented Dec. 2, 1919.

UNITED STATES PATENT OFFICE.

ALBERT CLOSE, OF PLAINFIELD, NEW JERSEY.

MILKING-MACHINE.

1,323,676.

Specification of Letters Patent.

Patented Dec. 2, 1919.

Application filed January 9, 1919. Serial No. 270,325.

To all whom it may concern:

Be it known that I, ALBERT CLOSE, a citizen of the United States, residing at Plainfield, in the county of Union and State of New Jersey, have invented certain new and useful Improvements in Milking-Machines, of which the following is a specification.

This invention relates to milking machines, and an object of the invention is to provide a sanitary milking machine which is comparatively simple in construction, and will lend itself to sterilization to prevent the accumulation of bacteria thereon in consequent transmission with the milk.

Another object of this invention is to provide a milking machine as specified, which comprises a pump or suction mechanism including a base block having lateral foot flanges thereon adapted to receive the feet of the operator to hold the suction apparatus securely in position which block is provided with a plurality of ways having communication with the suction pump and with a cow teat engaging member and also opening out through the edges or sides of the base block, said opened out ends being normally closed by removable plugs, so that for sterilizing purposes, the plugs may be removed to allow the boiling water or sterilizing liquid to pass freely and entirely into the suction apparatus.

Other objects of the invention will appear in the following detailed description taken in connection with the accompanying drawing, forming a part of this specification and in which drawings:

Figure 1 is a view of the suction or pump mechanism showing parts thereof in side elevation and parts in section.

Fig. 2 is a fragmentary edge elevation of the milking machine.

Referring more particularly to the drawings, 1 generically indicates the pump or suction mechanism of the milking machine, 45 which comprises the base slot or body 2 being substantially in shape and provided with laterally extending foot flanges or rests 3 upon its end at their lower edges which are adapted to receive the sole portions of the 50 feet of an operator to securely hold the feet in place as shown in Fig. 1 of the drawings. The body block 2 is provided with a pair of vertically extending ways near its opposite edge, each of which comprise various 55 portions of varying diameters. The upper portion of these vertical ways are relatively

large in diameter and are partially threaded for detachable connection with the cylinders 4 and 5 in which the pistons 6 are reciprocably mounted. The piston rods 7 which 60 are connected to the pistons 6 project upwardly through the removable cap 8 which forms closure for the upper ends of the cylinders 4 and 5. Suitable hand grips 9 are formed upon the upper ends of the piston 65 rods 7 to permit a firm grip thereon by the hand of the operator. The removable plugs 10 are inserted in the lower ends of these vertical ways forming closures therefor. A pipe 11 extends transversely across one side 70 of the body 2 near the bottom thereof and has communication with the vertical way directly above the lower closure plugs 10. An elbow pipe 12 communicated with the pipe 11 intermediate its ends and this pipe has a 75 connecting plug 13 formed upon its outer upper end. A plurality of relatively small metal tubes 14 are connected to the couplings 13 and they have hose or flexible conduits 15 connected to their outer free ends and 80 these conduits may be of any desired length, they providing coupling for connecting the tubes 16 to the pipe 14. The tubes 16 are preferably made of sterling silver and they have their ends rounded as shown at 17 to 85 prevent irritation when they are inserted into the teat of the cow as shown in Fig. 1.

Upon the upward stroke of the piston 6 in the cylinder 4, a suction is created through the tubes 16, down through the pipes 12 and 90 11 and into the vertical way in the body block which has communication with the cylinder 4 displacing the ball or checking valve 18 and allowing the milk to be drawn upwardly into the portion of the vertical 95 way above the check valve and also into the cylinder 4. Upon the downward or force movement of the piston 6 in the way 4, the milk which has been drawn into the cylinder 4 by the suction stroke of the piston is 100 forced therefrom through a transverse way 19 through the check valve structure 20 into the relatively shallow vertical way 21 from which it passes into the transverse pipe 22 and from this pipe outwardly through the 105 discharge nozzle 23 into a bucket or other suitable container not shown. Upon the down or force stroke of the piston 6 the check valve 18 will be closed, preventing the passage of the milk back into the pipe 11 110 and upon the suction stroke of the piston 6 in the cylinder 4 the check valve 20 will be

closed to prevent the drawing of milk from the pipe 21 back into the transverse way 19. The transverse way 19 opens out through one end of the body block 2 and a removable closure plug 24 is inserted in the outer end, to prevent the passage of milk outwardly therethrough while a removable closure plug 25 is inserted in the outer end of the way 21 which way opens out into the top of the body block. These removable plugs 10, 24 and 25 are adapted for removal when sterilizing the pumping mechanism of the milking machine so as to allow the sterilizing liquid to pass freely through all parts of the pumping structure. The body 2 is also provided with a second set of transverse and vertical ways corresponding to the ways 19 and 21 which have communication with the cylinder 5 so that the operation above set forth will be repeated during the movement of the piston 6 within the cylinder 5 and these pistons 6 in the cylinders 4 and 5 are adapted to alternate operation, thereby causing a constant suction through the pipe 12 and nipples or tubes 16 and consequently resulting in a constant flow of milk from the cow's udder into a receptacle until the quantity of milk has been removed from the cow's udder.

30 From the foregoing description and the drawings, it will be apparent that the milking machine has been provided wherein the suction force may be regulated manually, as each individual teat requires; one which will lend itself readily to sterilization and also one wherein the transmission of any bacteria from the cow teats or udder or the hands of the operator to the milk is entirely eliminated.

40 Changes in details may be made without departing from the spirit of this invention, but;

I claim:

1. In a milking machine, the combination, of a suction pump including a base block, a pair of parallel cylinders, carried by said block, pistons reciprocably mounted within said cylinders, milk inlet ways in said body block, having communication with said cylinders, whereby milk will be drawn into the body block and cylinders, upon the suc-

tion creating movement of said pistons, outlet ways in the block communicating with said pistons and check valves within said ways to control the passage of milk therethrough, said ways opening out at outer surfaces of said body block, and removable plugs forming closures for the outer ends of said ways to permit sterilizing of the body block.

2. In a milking machine, the combination, of a suction pump including a base block, a pair of parallel cylinders carried by said block, pistons reciprocably mounted within said cylinders, milk inlet ways in said body block having communication with said cylinders whereby milk will be drawn into the body block and cylinders upon the suction creating movement of said pistons, outlet ways in the block communicating with said pistons and check valves within said ways to control the passage of milk therethrough, said ways opening out at outer surfaces of said body block, and removable plugs forming closures for the outer ends of said ways to permit sterilizing of the body block, a pair of laterally extending foot receiving flanges formed upon the edges of said body block at its base.

3. In a milking machine, the combination, of a suction pump including a body block provided with a pair of vertically extending ways positioned one near each end of the body block, cylinders connected to the body block and extending into the upper ends of said ways, reciprocable pistons in said cylinder, a liquid inlet pipe having communication with said vertical ways near their lower ends, an outlet or discharge pipe, said body block provided with outlet ways having communication with said discharge pipe and said body block provided with transversely extending ways communicating with said outlet ways and said vertical ways, said vertical ways, outlet ways, and transverse ways opening out at one end in the outer surfaces of the body block and closure plugs mounted in said outer ends of said ways.

ALBERT CLOSE.

Witness:

GEORGE T. WOGLOM.
